UNITED STATES PATENT OFFICE

2,423,133

NECKTIE

Fred Wagner, Buffalo, N. Y.

Application October 9, 1943, Serial No. 505,657

2 Claims. (Cl. 2—150)

1

This invention relates generally to certain new and useful improvements in men's neck wear but more particularly to a ready-made or permanently-knotted four-in-hand tie.

It has for one of its objects to provide a tie of this character which is so designed and constructed as to avoid artificial appearance and effectually simulate a self or hand-made tie in shape and appearance, and which enables the knot portion to be adjusted at the will of the wearer to assume different angular positions relative to the collar.

Another object of the invention is to provide a four-in-hand tie which is simple and inexpensive in construction, which effectually retains the knot in its proper shape, and which is neat and tidy in appearance.

Other features of the invention reside in the construction and arrangement of parts herein-after described and particularly pointed out in the appended claims.

In the accompanying drawings:

Figures 1 and 2 are front and rear perspective views of a four-in-hand tie made in accordance with my invention. Figure 3 is an enlarged vertical section taken on line 3—3, Figure 1, showing the manner in which the tie is applied to the knot-form or core piece before being anchored thereto by stitching or the like. Figure 4 is a horizontal section thereof taken on line 4—4, Figure 3. Figure 5 is a detached perspective view of the knot-form or core piece. Figure 6 is a fragmentary perspective view of the tie in its untied position.

Similar characters of reference indicate corresponding parts throughout the several views.

In its preferred construction, this improved ready-made four-in-hand tie consists of a knot-form or core piece 10, a necktie 11 adapted to be permanently assembled or applied to the knot-form to thereby simulate the four-in-hand knot, and a collar-engaging band or neck piece 12 for detachably connecting the same to the collar of the wearer.

The knot form 10 is made of relatively thin sheet metal or like material and is substantially the shape shown in Figure 5 to provide a downwardly-tapering or an inverted, conical-shaped section 13 of substantially semi-circular shape in cross section and about which the tie is folded or wrapped to properly shape the knot. Extending laterally and rearwardly from the upper end of this conical section is an attaching flange 14 about which the top portion of the knot is wrapped and to which the attaching collar-engaging band

2

12 is secured. Any suitable means may be employed for anchoring the collar-engaging band to this flange, that shown in the drawings consisting of a pointed tongue 15 resulting from a V-shaped slit produced in such flange, the pointed tongue facing forwardly or toward the depending conical section 13 of the knot-form.

The tie 11, about midway of its ends, is adapted to be folded on itself as depicted in Figure 6 or looped lengthwise about the knot-form 10, in the manner shown in Figure 3, with the longer or front portion of the tie extending over the front or convex face of the conical section of the knot-form then rearwardly over the flange 14, and thence downwardly over the rear or concave portion of such conical section. Applied to the medial or that portion of the front side of the tie which extends over the conical section of the knot-form is a separate transversely extending portion 16 which is folded at its side edges about the corresponding edges of the front portion of the tie and secured thereto by stitching or the like thereby resulting in a false or loop-shaped portion which simulates the customary cross member of the four-in-hand knot. This transverse tie-portion 16 is of a width approximating that of the length of the conical section of the knot-form. By this construction, the upper and lower edges of the transverse portion 16 of the tie, which is preferably made of the same material as the tie and with the design thereof running in a direction to simulate a hand-tied knot, define the pronounced top and bottom edges or contour of the knot, while the tapered section 13 of the knot-form gives the conical shape to the knot.

After applying the tie to the knot-form in the looped manner shown in Figures 3 and 4, the contiguous portions of the tie overlying the front and rear sides of the conical section 13 are shaped snugly about the flange and convex front face of the knot-form, in the manner shown in Figures 1 and 2, with the opposite side edges of the tie meeting at the rear side of the knot-form, at which point they are firmly secured in place by stitching 17 or the like. That portion of the tie inwardly of such stitched edges is folded or crumpled into the hollow or concave rear portion of the knot-form to give the desired contracted appearance to the tie immediately below the knot. It will be noted from these figures that the top portion of the knot, which extends over the flange 14 of the knot-form, results in end openings 18 through which the collar-engaging band 12 extends, thereby providing a neat and protected

cover for this band at its point of connection to the flange.

By this construction, a ready-made four-in-hand tie is produced which is neat in appearance, and inexpensive in construction, and which effectually imitates the hand-made four-in-hand knot and at the same time avoids the artificial appearance heretofore prevalent in ready-made ties of this character. Furthermore, the construction of the knot-form and its attaching flange 14 enables the tie knot to be adjusted angularly relatively to the collar to suit the convenience or desires of the wearer. It will be noted, in this connection, that at the junction between the conical section 13 and the flange 14 of the knot-form there are provided notches 19 which permit such conical section to be bent within certain limits relative to the flange and thereby enable the wearer to adjust the knot so that it lies more or less flat or protrudes forwardly at an angle to the collar. 20

I claim as my invention:

1. A ready-made tie of the character described, comprising a knot-form, a necktie folded upon itself intermediate its ends in lengthwise relation about said knot-form and contracted transversely thereabout and securely fastened at its rear edges about the same, the front portion of the tie extending over and in contiguous relation to the front face of the knot-form having a self-contained false portion substantially in the

form of a loop-like strip having its ends extending about the side edges of the front portion of the tie and secured only at its ends to the rear of such front portion to simulate the contour of the upper and lower edges of the tie-knot, and means for detachably supporting the tie on one's collar.

2. A necktie of the four-in-hand type having on that portion thereof intermediate its ends, 10 and on the exposed front length thereof, a transverse loop-like strip simulating the customary tie-loop and defining the upper and lower edges of the tie-knot said strip being made of the same material as the tie and extending about the side edges of the exposed length of the tie and secured only at its free ends to the rear side thereof.

FRED WAGNER.
